UNITED STATES PATENT OFFICE.

PAUL BROWN KLUGH, OF CHICAGO, ILLINOIS, ASSIGNOR TO THE CABLE COMPANY, OF CHICAGO, ILLINOIS, A CORPORATION OF ILLINOIS.

SOLO DEVICE.

1,203,359.

Specification of Letters Patent. Patented Oct. 31, 1916.

Application filed August 23, 1910. Serial No. 578,577.

To all whom it may concern:

Be it known that I, PAUL BROWN KLUGH, a citizen of the United States, residing at Chicago, in the county of Cook and State 5 of Illinois, have invented a certain new and useful Improvement, in Solo Devices, of which the following is a full, clear, concise, and exact description, reference being had to the accompanying drawings, forming a part 10 of this specification.

My invention relates to automatic musical instruments and especially to a type of instrument operating in connection with a traveling perforated music sheet or record, 15 such as a player piano or piano player.

The invention contemplates securing certain advantageous results in connection with constructions likely to be found in instruments of this general class.

20 The invention contemplates the arrangement of such an instrument or parts of its mechanism or construction in such a way as to permit more than one use of pneumatic mechanism as may be desired without 25 interfering with the efficiency of the instrument or mechanism, or injuring or causing disadvantageous results in connection with the same.

I have shown the invention as applied 30 more particularly to a type of player piano which I have devised for obtaining solo effects, the instrument being conveniently arranged so that such solo effects are secured automatically through pneumatic mechanism 35 coöperating with the tracker board and traveling music sheet or record. It will be understood, however, that the invention is capable of being used in connection with other types of instruments, and 40 other mechanisms and constructions.

The particular type of instrument in connection with which I show my invention is made the subject matter of an application for patent filed by me April 8, 1910, Serial 45 No. 554,140, solo device for player pianos and the like.

The invention is shown applied to the pneumatic mechanism by which the solo effects are secured. By the invention applied 50 in this way the instrument can be controlled to permit playing either by hand in the usual way, or automatically by the music roll, without injuring or interfering with said pneumatic mechanism.

55 In the accompanying drawings Figure 1

is a vertical section of a player piano having solo mechanism similar to the mechanism of my aforesaid application for patent, said player piano also containing my present invention: Fig. 2 is an elevation 60 of a portion of the music roll showing a portion of the tracker board behind it; Fig. 3 is a perspective view of a portion of the mechanism of the instrument shown in Fig. 1; Fig. 4 is a view partly in elevation 65 and partly in section of a portion of said instrument.

The player piano shown in the drawings to illustrate the invention is, as stated hereinbefore, set forth so far as general features 70 are concerned in an application of mine already on file in the Patent Office, Serial No. 554,140. Therefore the general features of construction of this instrument will not require extended description.

Briefly considered the instrument has a tracker board 1, over which is advanced a music sheet 2, by some suitable or preferred type of mechanism not shown, the music being drawn from the usual music spool 3, 80 and wound upon a take-up roll 4. The instrument being preferably of the solo type previously referred to by me, the tracker board 1, has two sets of apertures 5, 5 and 6, 6, whereof the apertures 5, 5 are preferably the usual type of round aperture, and the apertures 6, 6 elongated apertures at one side of the apertures 5, 5. The music sheet 2, has two types of perforations 7, 7 and 8, 8, 7, 7 being the usual narrow perforations adapted to register with and open only the apertures 5, 5, and the perforations 8, 8 being wider than the perforations 7, 7 and each adapted to open both an aperture 5 and its associated side aperture 6.

The apertures 5, 5 are connected by pneumatic tubes 9, with pneumatic mechanism 10, by which the piano action 11 is operated. The apertures 6, 6 are connected by tubes 100 12 with supplementary pneumatic mechanism 14, peculiar to this type of solo instrument, by which the operation of the piano hammers 15 is controlled to produce solo effects. This control conveniently consists in normally shortening the hammer stroke so that the blow of the hammer will be slight or moderate, and the sounding of the note relatively moderate or soft, but at proper times and in connection with de- 105 110

sired notes lengthening the hammer stroke so that the blow will be longer and the sounding of the note relatively strong or stronger. The mechanism shown operates in this way as follows: The music sheet in traveling across the tracker causes the operation of the piano action in the usual way by the perforations 7, 7, and the tracker board openings 5, 5 and the pneumatic mechanism 10. The wide openings 8, 8, however, open also the tracker apertures 6, 6, thereby preliminarily actuating the corresponding pneumatic mechanism 14 so as to lengthen the corresponding hammer strokes and thereby produce accented or solo notes.

In the specific arrangement shown the pneumatic mechanism 14 comprises collapsible pneumatics, which are normally in their expanded positions as shown especially in Figs. 1, 3 and 4. The operation of this mechanism by the wide openings 8 causes the collapse of the corresponding pneumatics and thereby actuates sliding rods 16, operating with said pneumatics, so as to withdraw said rods and allow the hammers 15 to be retracted or moved forward to a long stroke position before being actuated by the usual operating mechanism. Referring more specifically to construction, the sliding rods 16 are conveniently mounted for sliding movement in a long rod or bar 17, serving as a support and guide for said rods, and itself being supported upon brackets 18 at the ends of the instrument. The forward ends of the rods 16 are provided with buttons 19 immediately in front of the loose or swinging leaves of the various pneumatics, so that the actuation or collapse of said pneumatics will move or shift said rods 16 forwardly.

Under various circumstances it becomes highly desirable to place the piano action or mechanism in such condition that it can be played manually or in other ways with the piano action in its usual condition or with the hammers retracted to their forward or long stroke position. In such case there is objection to collapsing the pneumatic mechanism 14 and holding the same collapsed for any extended period of time or for other reasons. I therefore arrange so that the hammers of the piano action may be retracted to their long stroke positions without collapsing the coöperating pneumatic mechanism 14. The arrangement I show herein for accomplishing that purpose is one simple and advantageous in form of arrangement, although of course others could be employed without departing from the invention. The arrangement shown in-

volves the provision of springs 20, 20, conveniently located to coöperate with the sliding rods 16, which latter are conveniently provided with buttons 22 in the rear of said springs, so that the latter may normally act upon the buttons 22 and hold the rods 16, 16 rearwardly projected and the hammers 15 in short stroke positions, springs 20 operating to return the rods 16, as required, after their retraction by the pneumatics. The rods 16 can be shifted in a forward direction, or in other words retracted to long stroke position, independently of the pneumatic mechanism 14, the rods 16 having loose or sliding connections with the loose leaves of said pneumatic mechanism, and as an arrangement for so shifting the rods 16, I show a series of fingers or plates 21, 21, arranged in the rear of the buttons 22 and supported and projected downwardly from a rocking bar 23, which is pivoted at its ends to brackets 24 at the ends of the instrument. Thus a rocking movement of the bar 23 will cause the fingers 21 to retract all of the sliding rods 16, and thus allow the hammers 15 to assume their long stroke positions, and at the same time it will be seen that this result is accomplished without interfering at all with the pneumatic mechanism, the sliding rods 16 having loose connections with the same. The rocking or oscillating bar 23 serves as a convenient support for the springs 20, previously referred to, and said bar is operated by some suitable form of mechanism, such as for example, as an arm 25, to which is pivotally connected a rod 26, extending down below the key bed and arranged for operation by a lever 27 and coöperating mechanism, which is fully described in my said other application and so need not be described here, it being sufficient to say that the movement of said lever 27 to one side will produce a vertical movement of the rod 26 and thereby cause a swinging movement of the arm 25 downwardly and a consequent forward movement of the fingers 22 to retract the sliding rods 16. A hammer rest rail 30 is arranged in the rear of the hammers 15.

The tracker board and music sheet herein set forth are disclosed and claimed in my co-pending application Serial No. 554,142, filed April 8, 1910, tracker board and music sheet.

It will be understood, of course, that this arrangement can be applied in other ways and to other mechanisms, and to different parts of the same mechanism, where the situation may require a result such as accomplished by the invention. It will be further understood that the arrangement shown herein can be changed and modified without departing from the invention.

What I claim is:

1. In a musical instrument in combination, a series of striking hammers, means for

- sustaining said hammers in short stroke position, pneumatics for acting on said sustaining means, the collapse of said pneumatics serving to withdraw said hammers into long stroke position, and mechanism for withdrawing said means into long stroke position while said pneumatics are inflated. 5
2. The combination with striking mechanism, of a member supporting said mechanism in short stroke position, a pneumatic having a loose connection with said member, which connection normally holds said member in position to hold the striking mechanism in short stroke position, and means for shifting said member independently of and relatively to said pneumatic. 10
3. The combination with striking mechanism, of means for controlling said mechanism comprising a collapsible pneumatic, a shiftable member operable by said pneumatic normally supporting said mechanism in short stroke position, and means for shifting said member relative to said pneumatic. 20
4. The combination with striking mechanism, of a collapsible pneumatic, a slide rod for supporting said mechanism in short stroke position, having a slideable connection with said pneumatic and adapted to be shifted by the same in one direction, and means for shifting said rod relatively to the pneumatic and in the direction in which it would be shifted by the operation of the pneumatic. 30
5. The combination with a collapsible pneumatic, of a rod having a slideable connection with said pneumatic but provided with a button coöperating with the pneumatic whereby the latter will shift the rod in one direction, said rod also having a second button, a spring operating upon the second button to shift the rod in opposition to the direction of movement of the pneumatic, a finger also acting upon said second button to shift the rod in opposition to the spring, and means for operating said finger. 40
6. The combination with a collapsible pneumatic, of a slide rod 16 having a loose connection with the loose leaf of the pneumatic and also having a button 19 adapted to be engaged by said loose leaf, a support for said rod 16, a button 22 on said rod, a rocking bar 23, carrying a spring 20 and a finger 21, both of which coöperate with said button 22 on said rod. 50
55. 7. The combination with a row of collapsible pneumatics, of a corresponding row of slide rods 16 having slideable connections with the swinging leaves of said pneumatics, said rods having buttons 19 adapted to engage the swinging leaves of said pneumatics and also having buttons 22, situated between the ends of the rods and away from the buttons 19, a bar 17 forming a guide for said rods 16, a rocking bar 23 carrying springs 20 adapted to act upon one side of the buttons 22 and also carrying fingers 21 adapted to act upon the other side of said buttons 22, and mechanism for rocking the bar 23. 60
8. In an automatic piano in combination, a series of striking hammers, means for sustaining said hammers in short stroke position, pneumatics for withdrawing individual hammers into long stroke position, and mechanism for withdrawing the entire series of hammers into long stroke position while maintaining said pneumatics in the short stroke position. 70
9. In an automatic piano in combination, a series of striking hammers, rods sustaining said hammers in short stroke position, and pneumatics for withdrawing individual rods to long stroke position, said pneumatics having a lost motion connection with said rods. 80
10. In an automatic piano in combination, a series of striking members, devices for sustaining the individual members in short stroke position, a second set of individual devices for actuating said sustaining devices, and additional actuating means for actuating said sustaining devices in unison, said individual actuating devices having a lost motion connection with said individual sustaining devices. 85
11. In an automatic piano in combination, a series of striking hammers, rods for sustaining said hammers in short stroke position having buttons thereon, a pivoted rail, two series of fingers attached to said rail contacting with opposite sides of said buttons, individual pneumatics for each of said rods to withdraw the same to long stroke position, and means for operating said rail. 90
12. In a musical instrument in combination, striking devices and actuating means therefor, a fixed rail for determining the long stroke position of said devices, mechanism for supporting said devices in short stroke position, actuating pneumatics for withdrawing said mechanism into long stroke position having lost motion connections therewith, and a pivoted rail for withdrawing said mechanism to long stroke position while said pneumatics are in short stroke position. 105
13. In a device of the class described in combination, striking devices and actuating means therefor, a fixed rail for determining the long stroke position of said devices, mechanism independent of said rail for supporting said devices in short stroke position, actuating pneumatics for withdrawing said mechanism into long stroke position having lost motion connections therewith, and additional means for withdrawing said mechanism into long stroke position while maintaining said pneumatics in short stroke position. 110
14. In an automatic piano in combination, 120
- 125
- 130

4. striking mechanism, shiftable members for controlling the length of stroke of said striking mechanism, normally sustaining said mechanism in short stroke position, pneumatics for operating said shiftable members and having a loose connection therewith, and springs operating independently of said pneumatics for returning said members to their original position after actuation of 10 said pneumatics.
5. 15. In an automatic piano in combination, a piano action comprising a plurality of units, a series of rods controlling said units as to long and short stroke position, pneumatics for operating said rods having a loose connection therewith, and means for shifting the entire series of rods to change the position of said units while said pneumatics are inflated.
6. 16. The combination of striking mechanism, shiftable members for controlling the length of stroke of said striking mechanism, pneumatics for operating said shiftable members and having a loose connection therewith; and adjustable means operating independently of said pneumatics upon said members.
7. 17. The combination with the piano hammers, of a series of shiftable abutments arranged to control the length of stroke of said hammers, pneumatics individually controlling said abutments, and an adjustable member combined with means for engaging said
8. abutments so as to permit said abutments to be collectively shifted to determine the extent of regulation to be exercised by said pneumatics, said shiftable member having means for flexibly and rigidly engaging said abutments.
9. 18. The combination with the piano hammers, of a series of abutments for limiting the length of stroke of said hammers, pneumatics controlling said abutments, and an adjustable member extending crosswise of said abutments and having a series of fingers 45 adapted to engage said abutments to move the same in a direction away from the hammers, and also having a series of flexible members adapted to move said abutments toward the hammers, but also adapted to permit the pneumatics to act to move the abutments away from the hammers.
10. 19. The combination with the piano hammers, of pneumatic devices combined with mechanism for individually regulating the 55 length of stroke of said hammers, and a swinging element carrying spring means acting upon said mechanism.
11. In witness whereof, I hereunto subscribe my name this eleventh day of August A. D., 60 1910.
- PAUL BROWN KLUGH.
